UNITED STATES PATENT OFFICE

113,925

DESIGN FOR DECORATIVE PAPER

Carl W. von Ehrn, Springfield, Mass., assignor to Holyoke Card & Paper Company, Springfield, Mass., a corporation of Massachusetts

Application September 16, 1938, Serial No. 79,935

Term of patent 3½ years

To all whom it may concern:

Be it known that I, Carl W. von Ehrn, a citizen of the United States residing at Springfield, in the county of Hampden and State of Massachusetts, have invented a new, original, and ornamental Design for Decorative Paper, of which the following is a specification, reference being had to the accompanying drawing, forming a part thereof.

The figure is a plan view of a piece of decorative paper embodying my new and ornamental design.

I claim:

The ornamental design for decorative paper,
as shown.

CARL W. VON EHRN.
